UNITED STATES PATENT OFFICE.

ALVIN L. JOHNSON, OF WORCESTER, MASSACHUSETTS, ASSIGNOR OF FORTY-EIGHT PER CENT TO W. GOULDING WARREN, OF HOLDEN, MASSACHUSETTS, AND FOUR PER CENT TO ALBERT E. FAY, OF WORCESTER, MASSACHUSETTS.

SCREW JACK.

Application filed February 3, 1922. Serial No. 533,971.

To all whom it may concern:

Be it known that I, ALVIN L. JOHNSON, a citizen of the United States, residing at Worcester, in the county of Worcester and 5 State of Massachusetts, have invented a new and useful Screw Jack, of which the following is a specification.

The principal objects of this invention are to provide a jack, preferably one of the 10 screw type, with a simplified operating mechanism; to provide means whereby the operator can shift the pawl in a simplified manner so as to change the direction of operation of the jack; to provide means 15 whereby he can do it by motion of the pawl operating handle in the same direction in which he is moving it to operate the screw; and to provide these features, without the addition of any movable parts, thus eliminating 20 the entire expense of applying the pawl shifting elements that are commonly used.

The invention also involves the provision 25 of a pawl carrying arm in connection with an operating handle so arranged that the screw can be raised by a substantially horizontal swinging motion of the arm and handle at the side of the jack and to provide means for frictionally holding the screw operating gear to prevent its moving in the 30 wrong direction accidentally.

Further objects and advantages of the invention will appear hereinafter.

Reference is to be had to the accompanying 35 drawings in which—

Fig. 1 is a front elevation of a screw jack constructed in accordance with this invention, parts being shown in section;

Fig. 2 is a plan of the same;

Fig. 3 is a central vertical sectional view on the line 3—3 of Fig. 2;

Fig. 4 is a transverse sectional view on the line 4—4 of Fig. 3;

Fig. 5 is a similar sectional view of the 45 line 5—5 of Fig. 3; and

Figs. 6, 7, 8 and 9 are enlarged detail views showing the positions of the operating pawl and the way in which it is shifted.

Although the invention is capable of general use, I have shown it as applied to a 50 screw jack of the type involving a base 10 and a casing 11, preferably integral with the base and extending upwardly therefrom.

This casing is provided with a vertical cylindrical passage therethrough from top 55 to bottom, in the opposite sides of which are an opposite pair of vertical grooves 12. The casing has a top 13 with a guide 14 constituting vertical continuation of the cylindrical passage. In this cylindrical passage 60 is shown the jack screw 15 having a rest 16 on the top. Near the bottom it is provided with a cross pin 17 extending beyond the screw and into both of the grooves 12. This provides means for preventing the rotation 65 of the screw while permitting it to move up and down in the casing.

On the screw threads of the screw 15 is a bevel gear 18 resting on the top of the lower part of the jack casing and located under 70 the cover 13. This is operated by a bevel operating gear 19 fixed to a horizontal shaft 20 having a bearing on the casing 11. The rotation of the gears raises or lowers the screw 15 as is well understood in this art. 75 The parts so far described constitute the main parts of a well known type of screw jack on the market and I have chosen to illustrate the invention as applied to this type of jack although it can be used on other 80 types.

I have shown the gear 19 as pinned by a pin 21 on the shaft 20 and I have shown the cover 13 as provided with a downwardly extending portion 22 which is provided with a 85 bearing for the outer end of the shaft 20. This portion 20 flares outwardly preferably to form two abutments 23 and 24 at opposite sides which serve an important purpose as will appear. On the end of the shaft is 90 a hand wheel 25 which can be used to rotate the gears and raise or lower the screw.

In the casing directly under the cover and bearing on top of the gear 18 I have placed a coil spring 26 which bears on the bottom 95 of the cover and on the top of the gear to

exert a yielding pressure on the gear and prevent its rotating accidentally in the wrong direction.

Swingingly mounted on the shaft 20 is a depending arm 30. This arm is shown as comprising a front and back plate both pivoted on the shaft and between them is a cross pin 31 on which is pivoted a double pawl 32 having two teeth for engaging the circular rack 33 on the edge of the gear 19. The pawl is shown as of V shaped construction to provide two divergent surfaces 34 for engagement with the conical end of a spring pin 35 located in the bottom of the arm 30. This spring pin automatically yields when the pawl is shifted and automatically engages the opposite surfaces 34 to hold the pawl yieldingly in either of its positions.

At the bottom the arm 30 is provided with a curved extension 36 to which is pivotally connected by a pin 37 a rod or tube 38. This makes an operating handle. But if it is desired to have a long handle I prefer to provide it with a screw threaded coupling 39 and connect it with an extension tube 40. Any desired number of these can be used and on the last one is a hand grip 41 for operating it.

At the end of the V shaped point between the two surfaces 34 there is a slight depression 42. This is to permit of the setting of the pawl in neutral position and hold it there by entrance of the point of the pin 35 into this depression.

In the operation of the device the jack can be handled in the manner indicated in Fig. 1 in which the metal handle 38-40 is employed as a carrying device coming against the edge of the casing and holding the jack in upright position while it is being set under the automobile or other device which it is desired to raise or lower. Thus the operator does not have to get under the car. The pawl is supposed at this time to be in neutral position. Having set the device in place, the operator can swing the handle 38-40 down to a nearly horizontal position, as indicated in dotted lines, and operate the jack from a considerable distance. This is done by pulling the handle toward the operator as far as it will go as shown in Fig. 6. The result of this is to bring the curved end 43 of the pawl 32 into contact with one of the abutments 23. Pressure applied by pulling the handle after these two parts come in contact forces the pawl over into the position shown in Fig. 6 and also Figs. 1 and 7.

The spring pin 35 then yieldingly holds it in that position. Now if the handle is pushed forward, in the direction indicated by the arrow in Fig. 6 the pawl ratches over the teeth 33 moving in that direction. Just

as soon as the operator swings the arm 30 back in the direction indicated in Fig. 7, the pawl will positively engage the teeth of the rack as shown in that figure and pull the gear 19 with it positively. These actions are due to the shape of the teeth on the pawl which is radial on the outside of each tooth and slanting on the inside. The result of the motion thus described is to turn the gear 18 in the direction to raise the screw 15. Now as long as the operator continues to swing the handle back and forth horizontally and thus swing the arm and not bring it far enough forward or back to touch either of the surfaces 23 or 24, the screw 15 will be raised by an intermittent motion as is common in this type of jacks.

When the operator is desirous to stop the upward motion and start the screw down, all he has to do is push the handle away from him to its limit. This results in bringing the parts to the position shown in Fig. 8 in which the pawl engages the abutment 24 and thus shifts from the raising to the lowering position. The further reciprocation of the handle and the oscillation of the arm 30 results in turning the gears in the opposite direction and lowering the screw. This will continue until the operator swings the handle back to the position shown in Fig. 6 and thus again shifts the pawl.

It is to be understood that in order to shift the pawl, the operator has to move the handle and the swinging arm to the limiting position in the direction contrary to that in which it is exerting force to move the load. It is quite natural that in pulling the handle forward to raise the load he may bring it too far forward swinging the pawl up against the surface 23 of the device. This will not shift the pawl. Similarly if in pushing the handle back to lower the load he goes too far it will not effect the operation. In other words, the natural operation of the device will not shift the pawl even if the operator exerts too much force. In order to shift the pawl he has to move the arm to the limit in the direction contrary to that in which he is exerting pressure to move the load in the direction in which it has been moving.

It will be seen therefore that the shifting of the pawl is an extremely easy matter, in fact is reduced to its simplest terms and yet there is no real danger for a green operator to accidentally shift the pawl in the wrong direction. While the operation of the device is reduced to the simplest terms, the mechanism is also reduced in the same degree, for nothing is required to shift the pawl except two fixed walls located in the right position. The jack can be lifted

and moved about in an upright position by bringing the parts to either of the positions shown in Fig. 1. The wall 44 or the edge of the frame prevent its tilting.

5. The spring 26 is arranged to bear on the gear 18 to exert a frictional pressure and prevent this gear being rotated accidentally in the wrong direction. The hand wheel 25 can be rotated to raise or lower 10 the screw when there is no load on it in accordance with the position of the pawl. This economizes in the time of setting the jack up to the work and disengaging it from the work when the operation is completed.

It is to be noted further that the operation of the device involves the location of the handle almost straight out in the rear or front and that the operator is free to 20 operate the handle at any desired height and can work the jack by a simple push and pull motion of the handle toward and from the jack instead of the hitherto universal oscillation of a handle about an inaccessible axis. This is an important feature of this invention because of the ease 25 of operation which is entirely incomparable with the usual practice. Furthermore, a comparatively small bar or pipe can be used for the handle because its operation does not result in any bending strain, as does the use of the usual oscillatory handle. The shifting of the pawl is accomplished in 30 exactly the same manner. This does away 35 with the necessity of crawling under a car for this purpose and eliminates all inconvenient and dirty operating arrangement in the form of chains or the like which are often employed for the manipulation of jacks.

Although I have illustrated only a single form of the invention I am aware of the fact that modifications can be made therein by any person skilled in the art without departing from the scope of the invention as 45 expressed in the claims. Therefore I do not wish to be limited to all the uses and construction herein shown and described, but what I do claim is:—

50 1. In a jack, the combination with a work rest, of a depending oscillatory arm, means comprising a pawl for causing the oscillation of said arm to raise or lower the rest, and means whereby the swinging of the 55 arm to its limiting position will shift the pawl.

2. In a jack, the combination with a work rest, of a depending oscillatory arm, means comprising a pawl for causing the oscillation of said arm to raise or lower the rest, and means whereby the swinging the arm in either direction to its limiting position will shift the pawl into a position to cause the rest to be moved in the direction in

which it is positively moved by the swinging of the arm in that direction. 65

3. In a screw jack, the combination with a screw and means for raising it and lowering it, comprising a gear, of a swinging arm, a pawl pivoted on the arm and having two teeth adapted to engage the gear to turn it in opposite directions as the arm swings on its pivot, and means for shifting the pawl when the arm is swung to its 70 limiting position. 75

4. In a screw jack, the combination with a screw and means for raising it and lowering it, comprising a circular rack or gear, of a swinging arm pivoted on the axis of said gear, a pawl pivoted on the arm and having two opposite teeth adapted to engage the gear to turn it in opposite directions as the arm swings on its pivot, and stationary means on the frame for shifting the pawl when the arm is swung to its 80 85 limiting position. 85

5. In a jack, the combination with a rest, a gear, means connected with the gear for raising and lowering the rest, of a pivoted depending arm, a pawl movably mounted on said arm and having two teeth, one adapted to engage the gear on one side of the arm and the other on the other side of the arm in accordance with the shifting of the pawl, whereby as the arm is oscillated on its axis it will rotate the gear in either direction in accordance with the position of the pawl, and a casing in which said gear is located having fixed walls or abutments in a position to be engaged by the pawl when the arm is swung to its 90 95 limiting position in either direction and to shift the pawl when so engaged. 100

6. In a jack, the combination with a raising and lowering means comprising a toothed wheel mounted to rotate on a horizontal axis, of an arm mounted to swing on said axis and normally depending therefrom, a pawl pivoted on said arm on an axis parallel with the axis of the wheel and having two opposite teeth projecting therefrom for engagement with the teeth of the wheel, the teeth of the pawl being inclined on their inner sides to allow the pawl to travel over the teeth of the wheel when the arm moves in one direction, the outer surfaces of said teeth being substantially radial with respect to the toothed wheel when the pawl teeth are in engagement with the 110 115 wheel. 120

7. In a jack, the combination with a raising and lowering means comprising a toothed wheel, of an oscillatory arm, a pawl pivoted on said arm and having two teeth projecting therefrom for engagement with the teeth of the wheel, the teeth of the pawl being inclined on their adjacent sides to allow the pawl to travel over the teeth of 125

the wheel when the arm moves in one direction, the opposite surfaces of said teeth being substantially radial with respect to the toothed wheel when the pawl teeth are 5 in engagement with the wheel, and a casing covering said wheel and comprising two opposite abutments located in position to engage the outer surfaces of said pawl when the arm is swung upwardly against them 10 and force the pawl to swing on its axis inwardly into engagement with the teeth of the wheel to reverse the operation of the jack.

8. In a screw jack, the combination with 15 the screw and means for raising and lowering it, comprising a gear, of an oscillatory arm pivoted on the axis of said gear, a double-toothed pawl pivoted on the arm adapted to engage the gear to turn it, and stationary means 20 on the frame for shifting the pawl when the arm is swung to its limiting position, said pawl having converging sides on the other side of its pivot, and a spring pin on the handle in position 25 to engage either of said sides to hold the pawl in either of its extreme positions in a yielding manner.

9. In a jack, the combination with a rest, 30 a gear, means connected with the gear for raising and lowering the rest of a pivoted arm, a pawl on said arm having two opposite teeth, adapted to engage the gear, whereby as the arm is oscillated on its axis it will rotate the gear in either direction 35 in accordance with the position of the pawl, and a casing in which said gear is located having means adapted to be engaged by the pawl when the arm is swung to its limiting position in either direction for shifting the 40 pawl, said pawl having converging sides, and a pointed spring pin for engaging said sides to yieldingly hold the pawl in either extreme position, the pawl also being provided with a small notch in its extreme vertex which the point of the pin is adapted to 45 engage to yieldingly hold the pawl in neutral position.

10. In a screw jack, the combination with 50 the screw and means for raising and lowering it, comprising a gear, of a swinging arm pivoted on the axis of said gear, a double-toothed pawl pivoted on the arm adapted to engage the gear to turn it, stationary means 55 on the frame for shifting the pawl when the arm is swung to its limiting position, and a handle pivoted to the bottom of said arm and adapted to be located in substantially horizontal position to operate the jack by a longitudinal forward and back motion.

11. In a screw jack, the combination with 60 the screw and means for raising and lowering it, comprising a gear, of a swinging arm pivoted on the axis of said gear, a double-

toothed pawl pivoted on the arm adapted to 65 engage the gear to turn it, stationary means on the frame for shifting the pawl when the arm is swung to its limiting position, and a handle pivoted to the bottom of said arm and adapted to be located in substantially 70 horizontal position to operate the jack by a longitudinal forward and back motion, said handle comprising a plurality of detachable sections adapted to engage the edge of said frame to hold the jack in upright position 75 when supported only by the handle.

12. In a screw jack, the combination with 80 a screw and means for raising it and lowering it, comprising a gear, a pair of bevel gears for connecting said gear with the screw, and a spring yieldingly engaging one of said bevel gears for preventing its moving accidentally, of a swinging arm, a pawl pivoted on the arm and having two teeth adapted to engage the gear to turn it in opposite directions as the arm swings on its pivot, and means for shifting the pawl when the arm is swung to its limiting position. 85

13. In a jack, the combination with a 90 movable load rest, of a depending arm pivoted on a horizontal axis at its upper end, means connected with the arm for raising and lowering the rest, and means connected with the arm, and extending from it substantially at the level of the lower end 95 of the arm when in use, for swinging the arm back and forth to operate the load rest.

14. In a jack, the combination with a 100 frame and a load rest movable thereon, of an arm pivoted on said frame, means connected with said arm for moving the rest when the arm is swung back and forth, and means connected with the end of said arm and extending therefrom for vibrating said arm to operate the rest. 105

15. In a jack, the combination with a 110 frame and a load rest vertically movable thereon, of an arm pivoted on said frame and adapted to assume a substantially vertical position when not in use, means connected with said arm for moving the rest vertically when the arm is swung back and forth to opposite sides of its neutral position, and means connected with the end of 115 said arm and extending therefrom for vibrating said arm to operate the rest.

16. In a jack, the combination with a 120 movable load rest, of a depending arm, means connected with the arm for raising and lowering the rest, means connected with the arm, and extending from it substantially at the level of the lower end of the arm when in use, for moving the arm back and forth to operate the load rest, and means for reversing the direction of motion of the rest, the last named means being operable by 125 said means for moving the arm.

17. In a jack, the combination with a

frame and a load rest movable thereon, of an arm pivoted on said frame, means connected with said arm for moving the rest when the arm is swung back and forth, 5 means connected with the end of said arm and extending therefrom for vibrating said arm to operate the rest, the first named means comprising a ratchet and pawl mechanism, and means whereby the ratchet and

pawl mechanism can be shifted by said 10 vibrating means itself to change the direction of motion of the rest upon the continuation of the operation of said vibrating means.

In testimony whereof I have hereunto 15 affixed my signature.

ALVIN L. JOHNSON.
